UNITED STATES PATENT OFFICE.

JOHN GREENWICH, OF FERNWOOD, IDAHO.

TORPEDO GUARD.

Application filed September 27, 1920. Serial No. 413,066.

This device relates to new and useful improvements in shields for ships of war, as well as for ships of commerce in time of war, and the principal object of the invention is to provide means to intercept torpedoes and the like and to remove them away from the ship.

Another object of the invention is to provide a submerged shield made up of a plurality of individual members, each member having an explosive in a cartridge associated therewith and adapted to be exploded by energy of water, driven by a quick moving torpedo, with some help or without any help of energy of the moving torpedo striking the yielding and entangling nets, that are associated with separate shields and are placed in front of the same. The force of this explosion will break the wood shield, made not very strong and especially designed for a breakage in middle, thus giving a passage to the gases and the gas driven currents of water to act upon the torpedo to remove the same away from the ship.

The explosion of the torpedo will probably not occur at all, because the primary action on the war head of the torpedo will be a comparatively mild one, on account of the protective nets held by coil springs in front of every shield and on account of the yielding of these springs, and nets, and shield under energy of water driven by the moving torpedo, or under energy of the torpedo itself, and on account of entangling 25 by the nets the firing mechanism of the torpedo, thus stopping a revolution of the fan of the torpedo and consequently locking the firing mechanism of the torpedo.

The torpedo can not explode by a shock, 40 because of before mentioned primary mild action on the torpedo and because the device is so constructed that the currents of water, as well as the broken parts of the device, will get at first side movements and may 45 exert only a side action on the torpedo. Besides this, these broken parts, moved by the force of explosion, are constructively protected by the nets, by the springs holding these nets, and by diagonal bars which are 50 not heavy and are hardened like springs. The more heavy piece, driven by the force of explosion, i. e., the piston is constructively protected by canvas and by two layers of shock absorbing watertight compound.

Movement away of the torpedo with some 55 side impulse, due to a noncoincidence in

most cases of a longitudinal axis of the torpedo with the direction of the resultant of forces, generated by an explosion of the cartridge or the cartridges, may give the 60 ship a possibility of passing the torpedo, and if the deflected torpedo shall hit the ship again, it will be moved and forced to the side again. Besides this, the mere process of forcibly removing the torpedo will probably 65 disturb the intricate mechanism of the torpedo, thus putting it out of order.

Even if the explosion of the torpedo does occur, this explosion can not occur close to the ship, because an earlier explosion of the 70 cartridge as well as some difference in the times of explosion of the charge in the cartridge and of the great mass of dry and wet guncotton of the torpedo will gain some 75 time, and this gained time will allow the removing of the torpedo to some distance, and even if this distance shall not be far enough, the final result of the explosion of the torpedo will be considerably diminished in force and in time by the explosion of the 80 adjoining shields, by the counteractions of the currents of water from the explosion of the torpedo and of the cartridges, and by the diminution of the fulcrum for the torpedo explosion, due to the gases from exploded cartridges.

Because the hulls of some ships may not be strong enough to withstand the effect or effects of explosions of the cartridges, these 85 hulls can be strengthened, if it should be necessary.

The resistance of the yielding parts of the device can be so calculated that it will prevent the explosion of the cartridges from the common sea waves. A special contrivance 95 locks the device, thus preventing an explosion from some powerful sea waves.

Separate torpedo guards are fastened to the separate planks of wood, and these planks are fastened to the hull of the 100 ship by a few screw bolts, thus making an adjustment of the device an easy and a quick job.

The invention also consists in some other features of construction and in the combination and arrangement of the several parts, to be hereinafter fully described, illustrated in the accompanying drawings and specifically pointed out in the appended claims.

In describing my invention in detail, reference will be had to the accompanying 110 drawings wherein like characters denote like

or corresponding parts throughout the several views, and in which:—

Figure 1 is a vertical sectional view of a portion of a ship provided with the shields and nets and with the locking device for the shields. Small details are omitted here. Section of links and operating lever is made on line P—Q of Figure 5.

Figures 2, 3, and 4 are details of fastening a frame for nets to the springs supporting the frame and of means to fasten the nets to the frame.

Figure 5 is a front view of means to operate the locking contrivance from inside of ship.

Figure 6 is a sectional view of push bolt that holds in position the lever for locking and unlocking of the device.

Figure 7 is a front view of one of the shields with the frame, bearing the nets, reposing on springs fastened to the shield, the nets being shown broken off.

Figure 8 is a section on line M—N of Figure 7.

Figure 9 is a detail of head for the plunger.

Figure 10 is an enlarged vertical view of the essential parts of the device with details.

Figure 11 is an enlarged sectional view of the cartridge mechanism of the device.

Figure 12 is two views of a metal plate of the shield.

Figure 13 is enlarged views of the collars with locks.

Figure 14 is an enlarged sectional view of the cartridge to show the grooves for grease and the flanged ring of variable strength.

Figure 15 is an enlarged sectional view of the cylinder for plunger, showing the grooves for grease, the hole for lock, and the valve opening for the outlet of the water.

My present invention is a further improvement and a reduction to the practice of my torpedo guards, filed at the office March 15, 1918; Serial No. 222,682.

In accordance with my present marking of the drawings, 1 indicates the hull of ship and 2 the planks to which the separate torpedo guards are fastened; 3 indicates the principal wood plank of separate shields. The shields gird the hull of ship like a belt and thickness and depth of such belt is dependent on the principles of torpedo attacks. 4, 5, and 6 indicate correspondingly the strips of wood reinforcing the principal wood plank 3 of the shields at edges and in center. These strips of wood are fastened to the principal wood plank of the shield by wood screws A, or by similar means.

The wood shield is designed to be broken by the force of explosion of the cartridge to give a passage to the gases and the gas driven currents of water to act upon the

torpedo. It is made not thick and is constructed not very resisting the breakage by force acting from behind, i. e., the explosion of a cartridge, but greatly resisting the forces acting on it in front, i. e., the sea waves. The thickness about one inch for the principal wood plank 3 and the same thickness for reinforcing strips of wood 4, 5, and 6 is most suitable for ordinary purposes. I prefer to use spruce, which is very flexible, not heavy, and is less liable to be split by action of sea waves. The size of the shield must correspond to the size of torpedoes and torpedo driven currents of water. I prefer to use the shields with an area less than an area of the cross section through the war head of a torpedo, to insure a more full action of the driven by the torpedo current of water, and on account of a less resistance and a better yielding of water behind a smaller shield. At the time of an explosion of a cartridge, on account of the inertia of the border parts of the shield and owing to the greater constructive resistance of the border parts, the shield will be broken at middle and broken parts, on account of a resistance of the border parts, will get a turning moment that will remove these parts at the sides thus giving a passage to the gases and to the driven by the gases currents of water to act upon the torpedo.

The wood shield is protected in front by three or more rows of nets 7, 8, and 9, composed of interengaging rings to entangle the firing mechanism of the torpedo. For this purpose the sizes of rings are different. The rings of net in front are about 2 inches in internal diameter, the next ones about 1 inch, and the last ones about $\frac{1}{2}$ inch.

The nets are held in position by nine coil springs 10, one at each corner, one at center, and four between corners; said nets are fastened by the wires B to the frame 11, which is made from spring pieces hardened like springs to prevent a bending of said pieces. The frame is connected to the springs 10 by eyes 11' and 11'' at the ends of spring pieces 11. To make this possible the front ends of springs 10 are shaped in eyes 12 to receive eyes 11' and 11'' of the frame 11. Other ends of the springs 10 are fastened to the reinforcing strips of wood 4, 5, and 6 by the nuts 13, and for this purpose the ends of the springs 10 adjoining to the strips of wood are enlarged straight pieces 14 and bear threads to receive the nuts 13.

The wood shields, as well as the nets connected to them, are spaced apart sufficiently to permit both of them to have movements independent of the other shields and their nets.

Each separate shield is yieldingly connected with the hull of ship by means of

plungers 15, made preferably from spring steel pieces hardened like springs to prevent a permanent bending of these pieces. One plunger is connected to each corner of the 5 principal wood plank 3 of the shield, and said plungers slide in cylinders 16 fastened to the plank 2 by wood screws 17 and in working order passing through the hull of ship 1 and through a flanged piece 18 fastened to the hull of ship from inside by the 10 screws 19. The heads of the plungers 15 are conical nuts 20, sunk in the principal wood plank of the shield and receiving the corresponding threads on the front ends of the 15 plungers 15. Recesses 21 in these nuts are intended to receive the forks of a nut driver. The conical form of the nuts is chosen here to facilitate the breakage of the shield under the action of the force of an explosion 20 of the cartridge.

A waterproof lining 22 around the cylinder 16, composed of canvas or some other stuff, is thoroughly saturated with wax and tallow compound, or the like, to prevent a 25 passage of water into the ship. The end of the cylinder 16 is kept closed by a screw bolt 23 which can be removed in time of greasing of said cylinder. A hole 24 with an opening 24' in the lower side of the cylinder 16 is an 30 outlet for water, if some should enter into said cylinder, and this hole will be automatically closed after firing of the device by a valve 26, owing to a considerable pressure of sea water under certain depth upon 35 said valve. A coil spring 27 one end of which 27' is screwed into the valve 26 and another 27'' into ring 25 supporting said spring screwed into the hole 24 of the cylinder 16, thus holding the opening 24' open in 40 an ordinary condition. Longitudinal grooves 28 inside of the cylinder 16 are intended to receive some kind of half solid grease thus alleviating the sliding of the plungers 15.

In the center of each shield is located a 45 plunger 29 which at its inner end is provided with a piston 30 that can slide in a cylinder 31. Longitudinal grooves 32 inside of said cylinder are filled with some 50 kind of half solid grease to produce an easy sliding of the piston 30. Said piston also 55 possesses a circumferential groove 33, filled with a mixture of tallow and hemp cut into very small pieces to facilitate a sliding of this piston, as well as for the purpose to keep moisture away from the cylinder 31.

The cylinder 31 is provided with a reduced extension 31' which forms the cartridge part of the device and in which is located the explosive charge 34. The end of 60 this extension fits in the socket 35 and is removably held therein by screw bolts 36, locked in position by pins 37. Said socket is fastened to the plank 2 by screw bolts 41, and the plank 2 is fastened to the hull of ship 1 by four screw bolts 42. It is ap-

parent that the construction of fastening the separate torpedo guards to the separate planks of wood makes an operation of fixing, and of separating said guards from the hull of ship an easy and a quick job.

A shoulder 31'' is formed at the junction of the cylinder 31 with the extension 31' and on this shoulder is seated a plate 38 with an explosive cap 39 screwed into said plate; by means of said cap, containing some good and effective detonator, the explosive charge in the extension 31' is ignited. The plate 28 is held in place by screw bolts 40. To keep the explosive charge and the cap perfectly dry I place a film C of pitch and wax compound, or the like, directly over the plate 38 and cover this by a layer of cement D. I also locate a packing ring 43 of rubber, or the like, in a recess formed in the plate 38.

A second shoulder 31''' is formed in the cylinder 31 and a coil spring 44 has one end seated against said shoulder and its other end seated against the bottom of the piston 30 to hold it in its forward position. The piston being prevented from leaving the cylinder by a flanged ring 45 secured to the enlarged end 31'''' of the cylinder 31 by screw bolts 46. The piston 30 is provided with a firing pin 47 which when said piston is moved inwardly will come in contact with 95 the explosive cap 39 and will explode the same.

The mentioned flanged ring 45 possesses the flanges 45' and 45'' unequal in thickness, and the thickness is gradually increased from 100 one end to the other. At the time of explosion of the cartridge and of breakage of said ring by the piston 30 the less thick, say upper part of the ring, will be broken first and the opposing resistance of stronger 105 lower part will generate a turning moment of the piston, say down below, and the action of the weight of the piston will help this downward movement of the same, thus giving a passage after breakage of the shield, 110 to the gases and to the driven by the gases currents of water to act upon the torpedo to remove the same away from the ship.

The wood shield is reinforced by a plate 115 of a soft metal 48 to hold the wood parts of the shield together, in case said parts shall be split by the action of sea waves. I prefer copper reinforcing plate painted with some waterproof paint, because such plate will not be much corroded by the sea water 120 and will also more easily yield under action of force of explosion of the cartridge. To facilitate the yielding of the plate at its middle and a breakage of the shield at middle part for the purpose of opening a 125 passage to the products of explosion to act upon the torpedo, said plate possesses rows of holes 49 at its middle portion, as it is shown in the Figure 12.

The bars 50 behind the plate 48 extend 130

diagonally from corner to corner of the plate, said bars being provided with eyes 51 to receive the plungers 15 and being held against metal plate 48 by nuts 52 on the mentioned plungers. The purpose of the bars 50 is to hold more firmly in working position both the plungers and the shield, to strengthen considerably the shield against forces acting upon it in front, i. e., against sea waves, and to diminish the force of the blow of the piston at the time of explosion of the cartridge, and for this purpose and for the purpose of preventing a permanent bending the mentioned bars are made from the spring steel and are hardened like springs.

Both the cylinders 16 and 31 I make watertight. Cylinder 16 by a mixture 53 of tallow with hemp, cut into very small pieces, and cover this mixture by a waterproof canvas 54, fastened to the flange of said cylinder by before mentioned wood screws 17. The cylinder 31 by a layer 55 of pitch, wax, and tallow compound, covered by a waterproof canvas 56; and by an inner layer of mixture 57 of tallow and hemp, cut into very small pieces, and cover this mixture by a waterproof canvas 58. Both canvases are fastened to the flange of said cylinder by screw bolts 59. Said watertight cover of the cylinder 31 is of a considerable thickness for the watertight purpose as well as for the purpose of a shock absorbing covering for the piston 30, in case said piston at the time of explosion of the cartridge will hit the torpedo.

A leakage at place of the screw bolts 40 holding the plate 38 I prevent by a pitch and wax compound 60 covered by a canvas 40 61 and held in place by screw bolts 62.

For the explosive charge I prefer to use the kinds that belong to the quick acting explosives and at the same time are least detonated by shocks and not very affected by moisture. It is apparent that the use of a good and a very energetic explosive may also gain some time, a fact of importance in case an explosion of the torpedo will actually occur.

50 A quantity of explosive may be so calculated that it will be sufficient to develop a force necessary to overpower not only an energy of water driven by the torpedo and the energy of the torpedo itself, but will give also some surplus of power, that will remove the water and the torpedo to some distance away from the ship.

The practice shows that the rate of burning gas from a certain explosive depends upon the size of grains used, upon the area of burning surface, upon the pressure, and upon the temperature. To shorten a duration of burning of the explosive to gain some time, in case the explosion of the torpedo will actually occur, I prefer to use a

granulated explosive. The burning surface of the explosive charge is constructively made not small, and the effect can be increased by a sufficient quantity of a good and effective detonator. The pressure of gases is here a favorable condition, because of a considerable resistance of the piston 30 owing to the flanged ring 45, which must be broken to give way to the said piston. The final result will be also increased by the resistance of water. 75 70

The resistance of the spring 44 inside of the cylinder 31 must be so calculated that combined with the resistance of the sliding parts of the device and with the resistance of water behind the shield, it will hold the pressure of water at a certain depth and will resist the common sea waves, but will yield under pressure of the energy of the water driven by a quick moving torpedo. 85

To prevent an explosion of the cartridges in rough seat the device possesses locks for the plungers 15, which are bolt pieces 63 bearing threads 63' near heads 63'' to screw these pieces into collars 64 embracing the cylinders 16. These bolt shaped locks may slide in holes 65 of the cylinders 16, and the direction of this sliding is made perpendicular to the sliding of the plungers 15. Adjoining collars 64 are knuckle joined by pins 64' locked by cotter pins 64''. Links 66 between couples of collars and links 67 adjoining the first collars are intended to relieve the possible strains upon the locks 63. 66', 66'', and 67' are pins and 66''', 66'''', and 100 67''' are cotter pins for knuckle joints of these links with collars. Links 67 are joined with a horizontal bar 68 by means of knuckle joined links 69 and 70 with pins 69', 69'', and 70' and cotter pins 69''', 69'''', and 105

70". Links 70 contain cylindrical parts 71, which can slide in the pillow blocks 72 fastened to the hull of ship 1 by wood screws 73. Said sliding secures a parallel motion of the bar 68 under the action of the lever 74 operating said bar by means of intermediary links 75 and 76. 77 and 78 are pins, 79 and 80 are cotter pins for knuckle joints of these links. A pin 81 with a cotter pin 82 knuckle joins link 76 with the operating lever 74. A bracket 83 with forks 83' is knuckle joined with the operating lever 74 and said bracket is fastened to the hull of ship 1 by wood screws 84. A pin 85 with a cotter pin 86 is an axis of rotation of the operating lever 74. A spring 87 is intended to facilitate the movements of said lever. This spring is joined with an eye 88' of a link 88 and said link is knuckle joined with the lever 74 by means of a pin 89 with a cotter pin 90. Another end of the spring 87 is joined with an eye 91' of a bracket 91, fastened to the hull of ship 1 by wood screws 92. The ends of the spring 87 are shaped in eyes 87' and 87" to receive the before mentioned eyes 88' 130

and 91'. It is apparent that a moving of the operating lever 74 down will be an easy job owing the considerable weight of the bar 68 and of the other movable parts of the locking contrivance. To raise the lever it will be necessary to overcome, besides the friction of the moving parts, the weight of the bar 68, as well as a weight of the other moving parts of the locking contrivance, and the 10 spring 87 performs a greater part of this job, and the resistance of this spring can be so calculated that a downward and an upward motion of the operating lever 74 will not be a hard job.

15 A push bolt 93, held in position by a coil spring 94, can slide in a cylindrical hole of a flanged pipe 95. A flange 95' is intended for fastening this pipe to the hull of ship by screw bolts 96, and an inner flange 95'' is intended to stop forward movement of said push bolt. A bottom part of the flanged pipe 95 contains a screw bolt 97 intended as a base for the spring 94. The push bolt 93 is constructed to receive a hole 74'' in an enlarged end 74' of the lever 74 and to hold this lever in its locking or unlocking position. E denotes the locking position of the push bolt and F the unlocking position of the same.

30 One turn of the lever 74 locks or unlocks the many vertical rows of the shields. The number of shields locked by single turn of the lever is limited only by the curvature of the ship, by a practicability and an accuracy of handling, and by a human force. I prefer to use for the locking a human force, as more intellectual and more sensitive than a machine force to prevent damage or putting the device out of order.

40 A resistance of the coil spring 44, inside of the cylinder 31, as well as a resistance of the sliding parts of the device, may be correspondingly calculated, as was before mentioned, and the locking will be necessary only at rough sea and in case of a storm, and practice shows that in time of a rough sea or a storm the torpedo attack from submarines, torpedo boats, and even from large war ships is, generally speaking, unsuccessful and lots 50 of times is not possible at all. Besides this, the locking contrivance is so constructed that for few men only a very short time will be necessary to unlock the device in case of a necessity.

55 It will be seen that a shield is provided which girds the hull of ship like a belt and said shield is made up of a plurality of independent shields. When driven by a quick moving torpedo the current of water strikes 60 one or more separate shields, said shield or shields by energy of water alone, or with some help of an energy of the torpedo, striking the yielding nets in front of the shield, will be forced inwardly, the plungers sliding in the cylinders and the firing pin 47 of

the piston 30 will explode the cap 39, thus firing the explosive 34 in the extension 31'.

The most effective range for torpedo attacks is one half mile or less, and fired at this distance the torpedo possesses a great 70 velocity, about 30 miles per hour, and drives the current of water with considerable velocity and consequently with considerable energy. The energy of moving matter is a great mechanical factor, and this factor, as 75 it is confirmed by an action of the hydraulic ram, is capable of overpowering a resistance of water in a comparatively calm condition. Because the separate shields, as were mentioned before, are small ones something 80 about one foot square, and the distance of the firing pin 47 from the explosive cap 39 is constructively made small, and a watertight covering on the front part of the cylinder 31 is constructively shaped parabolically, 85 or the like, and the energy of water driven by a quick moving torpedo is a great one, a side yielding of the water behind the shield will readily take place, and under action of the energy of the driven by the moving torpedo current of water, with some help or without any help of the energy of the torpedo, striking the yielding nets in front of the shield, will occur an explosion of the charge 34 in the cartridge 31', as was explained before. The resultant gases will 90 force the piston 30 outwardly, and because the flanged ring 45, as was before mentioned, possesses the flanges 45' and 45'' of unequal strength, a less strong, say upper flange, will be broken first, and the resistance of a stronger lower flange will generate a turning moment of the piston 30, that will remove it to the side, say down below, and a weight of the piston will help this downward motion of the same. It is apparent, 95 too, that the broken flanges 45' and 45'' will be removed to the sides by a generated turning moment of these pieces at the time of their breakage. Owing to the inertia of 100 the border parts of the shield and owing to a less constructive resistance of a middle part of the shield than the border parts, the wood parts of the shield, as well as the metal plate 48 of the shield with the holes 105 49 at its middle part, will be broken at middle, and the broken parts on account of a greater resistance of the border parts will generate a turning moment, that will remove these parts to the sides, thus opening 110 a passage to the gases and to the driven by the gases currents of water to act upon the torpedo to remove the same away from the ship. Because the longitudinal axis of the 115 torpedo in most cases does not coincide with the direction of the resultant of forces, generated by the explosion of cartridge or cartridges, the torpedo will get not only a forward impulse it will get also some side impulse.

The explosion of the torpedo will probably not occur at all, owing to the special construction of war head of torpedo with its firing pin, whiskers, and revolving fan, owing 5 to the yielding and entangling nets 7, 8, and 9 in front of every shield, and owing to a comparatively mild primary action of the gases and of thrown by gases currents of water; said mild action will be caused by 10 primary counteractions of currents of water driven by the moving torpedo and by an explosion of the charge 34 associated with every shield; at the time of said counteractions of currents of water will be some 15 comparatively calm condition of currents of water, which probably will check the revolution of the fan of the torpedo, if this revolution shall not be affected positively before by the entangling nets 7, 8, and 9. 20 It is a well known fact that used at present torpedoes are dangerous only when they are actually under way. In a restful condition, as well as in a case of not quick enough motion, the little fan prevents the 25 firing pin from driving in. The motion of the torpedo through water causes this fan to revolve, and after the torpedo has reached a certain speed, will compel the fan to spin itself off, thus releasing the firing pin from 30 its restraining position. When a torpedo travels with a velocity of 25 to 40 miles per hour, the front part of the firing pin is subject to considerable pressure, which must be constructively restrained to avoid an 35 explosion of the torpedo while under way. To secure an explosion of a moving torpedo it must meet some solid object, which will concentrate instantly a great energy of the moving torpedo on the firing pin. In the considered here case the powerful energy of the water driven by the moving torpedo will diminish the confronting resistance of the coil springs 10 associated with the shield and will in many cases explode the charge 40 34 in the cartridge 31' just before the torpedo itself will reach the nets 7, 8, and 9, and if the torpedo itself does reach said 45 nets before an explosion of the sudden explosive 34 in the cartridge 31', the firing mechanism of the torpedo will be entangled in time of yielding the nets as well as the coil springs 10 holding these nets and the coil spring 44 inside of the cylinder 31, and the result will be a locking of the firing 50 mechanism of the torpedo, owing to a stopping or a retarding of revolutions of the revolving fan of the firing mechanism of the 55 torpedo.

An explosion of the torpedo may not also 60 occur from a shock because, as was explained before, the piston will be removed to the side, and the protective nets 7, 8, and 9, as well as the springing diagonal bars 50, will constructively separate the war 65 head of the torpedo from the piston 30.

Besides this, the front part of the piston 30, as was mentioned before, is covered with the canvases 56 and 58 and by two layers 55 and 57 of a soft and shock absorbing watertight compound. 70

Removing the torpedo to the side will give the ship the possibility of passing said torpedo, and if the torpedo so removed will hit the ship again, it will be removed again. Besides this, a mere process of forcibly removing the torpedo will probably 75 disturb an intricate mechanism of the same, an adjustment of the hydrostatic piston, pendulum, or even the Obry gear which is a complicated contrivance too, and this disturbance will probably lessen the danger from the torpedo. 80

If the explosion of the torpedo does actually occur, this explosion may not occur close to the ship, because a difference in times 85 of explosion of the cartridge of the device and of war head of the torpedo, as well as the use for the cartridge of an explosive very quick acting and of a sufficient quantity of a good and effective detonator, will gain some 90 time, as was mentioned before, and this gained time will allow a removing of the torpedo to some distance away from the ship, and even if this distance shall not be far enough, the final result of the explosion 95 of the torpedo will be considerably diminished in force and in time by an explosion of the adjoining shields, by counteractions of currents of water from both explosions of the torpedo and of the cartridges of 100 the device, and by a diminution of the fulcrum for the exploded torpedo, due to the gases from exploded cartridges. 105

If by action of some one factor some cartridges do explode and there is no time to 105 put new ones, the danger from torpedoes is prevented by a fact that the size of separate nets and associated with them shields is less than the size of a cross section through the war head of the torpedo, and the adjoining 110 members will protect the ship from torpedoes.

Before a great storm it will be better to remove the torpedo guards from the ship, and this operation on account of before mentioned constructive features of the device is an easy and a quick job. Strictly speaking, there is a necessity to keep steadily the torpedo guards around the ship only in war time or before a battle and at all other times 115 the guards may be removed from the ship and stored in some place close to the hull of ship for a convenience in handling of the same. Because separate planks 2 to which the separate torpedo guards are fastened are 120 combined with the cylinders 16, fastened to the plank 2 by the wood screws 17, at the time of removing of said guards from the ship an undesirable hole will be produced in the hull of the ship, and all such holes must 125 130

be immediately closed by a cover 98, supplied with a strip of leather 99 and a hinge 100, that enables said cover to revolve in a vertical plane. A screw bolt 101 at the end 5 of the cover 98 can press snug and watertight the mentioned cover to the flanged piece 18. Screw bolts 102 and 103 are fastening bolts for the hinge 100. Screw bolts 104 are intended to close other undesirable 10 holes, which will be produced in the hull of ship at the time of withdrawing the screw bolts 42, fastening the planks 2 bearing the separate torpedo guards to the hull of ship 1. Chains 105 receive eyes 104' of the screw 15 bolts 104 and are attached to the hull of ship 1 by wood screws with eyes 106 to prevent the losing of these necessary screw bolts.

Torpedo guards must be inspected from 20 time to time, especially in time of war, to insure a successful action in a time of necessity, and this procedure, on account of simple constructive features of the device, is a quick and an easy job.

25 To protect parts of torpedo guards from the action of sea water said parts must be coated correspondingly. The wooden parts must be painted with some waterproof paint, and the metallic parts must be painted or 30 coated with some metal resisting the action of sea water; sliding parts must be kept well greased to insure better results. It is apparent that the plungers 15 may be lubricated at any time from inside of ship after unscrewing the screw bolts 23. The piston 30, as well as the inside of the cylinder 31, must be well greased in time of assembling parts of said cylinder to prevent any rusting. The longitudinal grooves 28 inside of the cylinder 16, as well as the grooves 32 inside of 35 the cylinder 31 and a circumferential groove 33 of the piston 30, must be well filled with before mentioned half solid grease to insure an easy sliding of the plungers 15 and the piston 30.

40 It is thought from the foregoing description that the advantages and novel features of my device, which forces the unexploded torpedo away from the ship, will be readily apparent. The device can be very useful for 45 the costly war ships, because the damage from a torpedo, if some occur, can not be, as was explained before, a great one, thus preventing a sinking of the costly war ship. The device can be also useful as a guard 55 from mines and other floating dangers for the ships.

The using of my device will be also not 60 very detrimental, because every explosion of the cartridge destroys only movable and less costly parts of the device, the cylinders 16 for the plungers 15, as well as the firing cylinder 30, will be probably not damaged at all, and the broken flanged ring 45 may 65 be replaced by a new one.

At present some torpedoes are supplied with a lance head, that can go through the commonly used nets, so making nets alone almost useless; said nets are kept steadily around the ships and at a considerable distance, so diminishing the velocity of the ship, but my device is kept close to the ship at a distance about one foot and half, so not very diminishing the velocity of the ship. Besides this, my device, as was explained 70 before, is composed of separate members fastened to the separate planks 2, that may be easily and quickly fastened to the hull of ship 1 by four screw bolts 42 and may be evenly quick removed from the hull, thus 80 making the keeping of the device steadily around the ship not a necessary matter in time of peace.

Some torpedoes are supplied with gun barrels, loaded with an explosive projectile, 85 and for such kinds of torpedoes my device is more useful than the commonly used nets, on account of the considerable yielding means of the nets and of the shields and on account of a comparatively mild primary action of 90 the gases and of the water on the war head of the torpedo, due to the counteractions of the currents of water driven by the moving torpedo and of the currents of water thrown by the force of the explosion of the cartridge or the cartridges, as has been explained before.

I desire it to be understood that I may 95 make slight changes in the construction and in the combination and arrangement of the several parts, provided that such changes fall within the scope of the appended claims.

What I claim is:—

1. A shield for ships comprising a plurality of separate shields yieldingly carried by 105 the hull, and explosive means associated with the shields to be exploded by the backward movement of the shields.

2. A shield for ships comprising a plurality of separate shields yieldingly carried by 110 the hull, a plurality of plungers carried by the shields, cylinders associated with the hull and receiving said plungers, springs for holding the plungers in their outward position, explosive means carried by some cylinders and firing means associated with some plungers for exploding the charge.

3. A shield for ships comprising a plurality of separate shields yieldingly carried by 115 the hull, cylinders associated with the hull, plungers secured to the shields and sliding in said cylinders, some cylinders having a portion for receiving an explosive charge, pistons connected with some plungers and sliding in suitably enlarged cylinders, a 120 spring in said enlarged cylinder for holding both piston and plungers in position, firing means connected with the piston for exploding the charge and constructive means producing a breakage of affected shield at mid- 125 130

to open way to the products of explosion to act upon the torpedo.

4. A shield for ships comprising a plurality of separate shields yieldingly carried by the hull, portions of every shield being of unequal strength to afford a breakage of shield at middle under action of exploded charge, explosive means associated with every shield to be exploded by the backward movement of affected shield to remove the torpedo away from the ship, entangling means for the firing mechanism of torpedo to prevent an explosion of the same; a locking contrivance of device and system of links to operate said locking contrivance.

5. A shield for ships comprising a plurality of separate shields yieldingly carried by the hull, nets in front of every shield associated therewith, cylinders combined with the hull of ship, plungers associated with the shields and sliding in said cylinders, spring means for holding the plungers in their outward position, explosive means carried by some cylinders, firing means associated with corresponding plungers for exploding the charge; a locking contrivance for the plungers and system of links to operate said locking contrivance.

6. A shield for ships comprising a plurality of separate shields yieldingly carried by the hull, yielding nets in front of the shields associated therewith, spring means producing said yielding of the nets, cylinders penetrating the hull of ship, plungers secured to the shields and sliding in said cylinders, central cylinders being enlarged and having an extension for receiving an explosive charge, a piston connected with the central plunger and sliding in an enlarged cylinder, a spring in said cylinder for holding piston in position, firing means connected with the piston for exploding the charge, constructive means producing a breakage of affected shield at middle to open way to the products of explosion to act upon the torpedo; a locking contrivance for the plungers, system of links to operate said contrivance and operating lever associated with the links and with said contrivance.

7. A shield for ships comprising a plurality of separate shields associated with separate planks, said planks removably fastened to the hull of ship, yielding means for said shields to accomplish an ignition of an explosive associated therewith, constructive means to produce a breakage of affected shield at middle to open way to the products of explosion to act upon the torpedo, yielding nets in front of every shield associated therewith, said nets composed of interengaging rings to entangle the firing mechanism of torpedo to prevent an explosion of the same, cylinders penetrating the hull of ship and means to make this penetrating watertight and safe for ship, plung-

ers secured to the shields and sliding in said hull cylinders, central cylinders being enlarged and having an extension for receiving an explosive charge, a piston connected with the central plunger and sliding in said enlarged cylinder, a flanged ring in the enlarged cylinder to retain the outward movement of piston, said ring with flanges of unequal strength to generate a turning moment of the piston under action of exploded charge, a spring in enlarged cylinder for holding the piston and plungers in their outward position, firing means connected with the piston for igniting the charge; a locking contrivance inside of ship to stop movements of the plungers to prevent an ignition of the charge, said contrivance being in shape of bolts screwed into collars embracing separate cylinders for the plungers, system of links to operate said contrivance from inside of ship by lever, and means to stop movement of said lever.

8. A shield for ships comprising a plurality of separate shields, associated with separate planks, said planks removably fastened to the hull of ship, reinforcing bars for the shields, yielding means for the shields to produce an explosion of the charge associated therewith by energy of water driven by moving torpedo or by a combined energy of water and torpedo, constructive means for breakage of affected shield at middle to open way to the products of explosion to act upon the torpedo, nets in front of separate shields associated therewith to entangle the firing mechanism of torpedo, said nets composed of interengaging rings and fastened to the frame held in position by springs associated with said frame and with the shield, cylinders penetrating the hull of ship and means to make this penetrating watertight and safe for ship, plungers secured to the separate shields and sliding in mentioned cylinders and lubricating means for the same, central cylinders being enlarged and having an extension for receiving an explosive charge, a piston connected with central plunger and sliding in the enlarged cylinder and lubricating means for the same, a flanged ring in the enlarged cylinder to retain the outward movement of piston, said ring with flanges of unequal strength to generate a turning moment of piston under action of exploded charge, a shock absorbing and watertight covering for said piston, a spring in enlarged cylinder for holding the piston and plungers in their outward position and firing means connected with the piston for exploding the charge; a locking contrivance inside of ship for the plungers to prevent an ignition of the charge, said contrivance in shape of bolts sliding in corresponding holes of cylinders for plungers, said bolts screwed into collars embracing the separate cylinders, system of links and lever

to operate said locking contrivance from inside of ship, push bolt to hold lever in its locking or unlocking position and spring means to alleviate operating of said lever.

- 5 9. A shield for ships comprising a plurality of separate shields spaced sufficiently to permit independent movements of every one, said shields associated with separate planks, said planks removably fastened to
- 10 the hull of ship, springing diagonal bars for the shields, reinforcing plate for the shield with holes in middle to afford a breakage of the shield at middle by force of explosion of the charge, yielding means for the shields
- 15 to accomplish an explosion of the charge associated therewith by energy of water driven by moving torpedo or by combined energy of water and torpedo, yielding nets in front of separate shields associated there-
- 20 with to entangle the firing mechanism of torpedo, said nets composed of interengaging rings and fastened to a springing frame, said frame held in position by spring associated with the frame and with the shield,
- 25 cylinders penetrating the hull of ship and means to make this penetrating watertight and safe for ship, plungers secured to the shield and sliding in said hull cylinders and lubricating means for the same, central cylinders being enlarged and having an exten-

sion for receiving an explosive charge, a piston connected with central plunger and sliding in said enlarged cylinder and lubricating means for this cylinder and for the piston, a flanged ring in said cylinder to retain the outward movement of piston, said ring with flanges of unequal strength to generate a turning moment of the piston under action of exploded charge, a shock absorbing and watertight covering for the piston, a spring in the enlarged cylinder for holding the piston and the plungers in their outward position, firing means to keep said charge and explosive cap perfectly dry; a locking contrivance inner of ship to stop movements of the plungers to prevent an explosion of the charge, said contrivance in shape of bolts sliding in corresponding holes of cylinders for plungers, said bolts screwed into collars embracing said cylinders, system of links to operate locking contrivance from inside of ship by a lever, push bolt to hold said lever in its locking or unlocking position and spring joined with the lever to alleviate operating of this lever.

Signed at Fernwood, in the county of Benewah, and State of Idaho, this 21 day of September, 1920.

JOHN GREENWICH.
